(57) **CLAIM**

The ornamental design for a firearm extractor adjusting tool, as shown and described.

DESCRIPTION

FIG. 1 is a perspective view of the firearm extractor adjusting tool showing my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right-side elevation view thereof; and,

FIG. 7 is a left-side elevation view thereof.

The broken lines shown in the drawings illustrate portions of the firearm extractor adjusting tool that form no part of the claimed design.
